CLAIM

The ornamental design for a foldable mobile phone, as shown and described.

DESCRIPTION

FIG. 1 is a perspective view of a foldable mobile phone shown in an unfolded state;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the foldable mobile phone shown in FIG. 1 in a first folded state;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a perspective view of the foldable mobile phone shown in FIG. 1, in a seconded folded state; and,

(Continued)

FIG. 18 is another perspective view thereof.
The shade lines in the figures show contour.
